DFS. 2055

1 Frederick A. Giles, of New York, N.Y.

Letters Patent No. 2055 Dated May 9, 1865.

Design for the Top Plate and Balance Cock of a Watch.

The scheme is referred to in these Letters Patent as making part of the same.

or or or

to all whom it may concern:

Be it known that I, Frederick A. Giles, of the City, County and State of New York, have invented a new Design for the Top Plate and Balance Cock of a Watch; and I do hereby declare that the following is a full, clear and exact description of the same, reference being had to the accompanying drawings forming part of this specification, in which:

Figure 1 is a plan view of the top plate and balance cock.

Figure 2 is an edge view of the same.

Similar letters of reference indicate corresponding parts in both figures.

A is the top plate of nearly semicircular form, as shown in fig. 1, except that it has starting from near its centre a, where comes the central spindle, an arc formed offset b, to form the indicator scale of the regulator, the said offset meeting the balance cock B, and being concentric with the central hole c, which receives the balance arbor. The outer edge e of the said cock is concentric with the centre a, and outer semicircular edge of the plate A.

The inner edge of the plate A has a salient curve g, concentric, or nearly so, with the hole h, which receives the arbor of the main spring and also entering curve i connecting the curve with the semicircular edge f. On the opposite side of the arc formed offset b, the inner edge of the plate has a salient curve j, concentric with the centre a, meeting in an angle, k, arc-entering curve l.

DES. 2055

2 which unites with a salient curve in, which is connected by a concave curve in with the semi-circular edge of... The greater portion of the upper surface of the plate A, is a plane, the outer margin of which is concave with the centre a, and the outer portion of between this margin and the edge b is concave depressed, the under surface of the said plate is flat, except that there is formed in it an irregular cavity c, shown in fig. 2, commencing at its inner edge and extending back toward the outer edge, so far as the dotted line c shown in fig. 1.

What I claim and desire to secure by Letters Patent is the design and configuration of the top plate and balance cock of a watch, substantially as herein described, and represented in the accompanying drawings.
